(57) **CLAIM**

The ornamental design for a cowl assembly for a vehicle.

DESCRIPTION

FIG. 1 is a top, front, left perspective view of a cowl assembly embodying our new design;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The ornamental design which is claimed is shown in solid lines in the drawings. The portions of the design shown in broken lines or dashed lines are included for the purpose of illustrating environment and form no part of the claimed design.
